Primary Examiner — Mary Shannon Malley*Assistant Examiner* — Lee D. Starr(74) *Attorney, Agent, or Firm* — Frost Brown Todd LLC(57) **CLAIM**

The ornamental design for an extension cord lock and in-line tap assembly, as shown and described.

DESCRIPTION

FIG. 1 is a top perspective view of an extension cord lock and in-line tap assembly, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The dash-dash broken lines in the drawings depict portions of the extension cord lock and in-line tap assembly that form no part of the claimed design.
